(57) CLAIM

The ornamental design for a kit for organizing medical supplies as shown and described.

DESCRIPTION

FIG. 1 is a perspective view of a kit for organizing medical supplies according to the present application;

FIG. 2 is a perspective view of the kit for organizing medical supplies of FIG. 1 shown with the kit opened up;

FIG. 3 is a front view of the kit for organizing medical supplies of FIG. 2;

FIG. 4 is a rear view of the kit for organizing medical supplies of FIG. 2;

FIG. 5 is a right side view of the kit for organizing medical supplies of FIG. 2;

FIG. 6 is a left side view of the kit for organizing medical supplies of FIG. 2;

FIG. 7 is a top view of the kit for organizing medical supplies of FIG. 2;

FIG. 8 is bottom view of the kit for organizing medical supplies of FIG. 2;

FIG. 9 is a perspective view of the kit for organizing medical supplies of FIG. 2 shown with medical supply bags removed and an included stretcher visible;

FIG. 10 is a perspective view of the medical supply bag of FIG. 2;

FIG. 11 is a perspective view of the kit for organizing medical supplies of FIG. 2; and,

FIG. 12 is a perspective view of the kit for organizing medical supplies of FIG. 2.

The broken lines in all views are for the purpose of illustrating environmental structure and form no part of the claimed design.

1 Claim, 10 Drawing Sheets
